UNITED STATES PATENT OFFICE.

CHARLES A. PRATT, OF CHICAGO, ILLINOIS, ASSIGNOR TO THE GOODMAN MANUFACTURING COMPANY, OF CHICAGO, ILLINOIS, A CORPORATION OF ILLINOIS.

MINING-MACHINE.

1,249,823.

Specification of Letters Patent. Patented Dec. 11, 1917.

Application filed October 31, 1910. Serial No. 589,836.

To all whom it may concern:

Be it known that I, CHARLES A. PRATT, a citizen of the United States, residing at Chicago, in the county of Cook and State 5 of Illinois, have invented a certain new and useful Improvement in Mining-Machines, of which the following is a specification.

This invention relates to mining machines, and has for its object to provide a new and 10 improved device of this description.

The invention is illustrated in the accompanying drawings, wherein—

Figure 1 is a plan view of a machine embodying the invention;

15 Fig. 2 is a sectional view taken on line 2—2 of Fig. 1;

Fig. 3 is a plan view of the device illustrated in Fig. 1, showing the position of the parts as the machine approaches the wall of 20 the mine;

Fig. 4 is a plan view showing the position of the parts at the end of the cut.

Like numerals refer to like parts throughout the several figures.

25 Referring now to Fig. 1, there is illustrated a mining machine having a frame 1, with a cutter projecting therefrom, the cutter in this instance consisting of the cutter chain 2 moving about the cutter arm 3, the 30 cutter chain being provided with a series of cutters 4 which act upon the material to be cut.

In the use of the machine the cutter projects into the coal, or other material, as 35 shown in Fig. 1, and the entire machine is then moved laterally to form the cut. This lateral movement is produced by a flexible power transmitting device 5, which is connected with a rotating part 6 mounted on 40 the frame of the machine, and adapted to be rotated by a motor 1^a on the machine, preferably the same motor that actuates the cutter chain. The part 6, as herein shown, consists of a drum about which the flexible 45 power transmitting device is wound. This drum is operatively connected with the motor in any desired manner, as for example, by the gears 2^a, worm 3^a, controlling clutch 5^a and gears 6. This flexible power transmitting device is connected with a fixed part 7, located at a suitable point, and preferably passes about a wheel 8 connected with the frame of the machine. In view of the fact 50 that the resistance to the lateral feeding movement of the machine is due to the cut-

ters, which project from the frame, and which must cut away the coal before lateral movement of the front end of the machine can take place, it will be seen that there will be a tendency for the frame end of the machine to feed forward too rapidly, and some means must be provided for preventing this and retarding the movement of the rear end of the machine. As herein shown, in order to prevent the too rapid movement 60 of the rear end of the machine, I provide an adjustable arm 9, extending from the rear end of the machine. As shown in Fig. 1, this arm 9 is movably connected to the frame, as by being pivoted to the part 10 upon which the drum 6 is mounted. This arm is preferably adjustable in length, which adjustment may be secured by providing a sleeve having a controlling hand-wheel, or the like, 12, the sleeve being provided with right and left-hand threads which engage right and left-hand threads on the sections 13 of the arm. The arm 9 is removably connected in position so as to hold in place an engaging part 14 adapted 70 to movably contact with the flexible power transmitting device 5, and in the construction shown in Fig. 1, said arm 9 is removably connected with the brace 17 which acts as a resisting part to resist movement of said arm and of the rear end of the machine 75 which tends to move faster than the cutter arm due to the resistance to the lateral movement of the front end of the machine produced by the engagement of the cutters with the coal. The part 14 may be of any desired construction, and, as herein shown, has two engaging faces 15, 16 (see Fig. 2), between which the flexible power transmitting device passes. The face 90 16 is preferably the face of a pulley, so as to reduce the friction as the pressure comes upon this face. The part 14 is connected with the frame of the machine in any desired manner, as by means of the brace 17. 100 As illustrated in Fig. 1, this brace is removably connected with the frame of the machine by being connected with the shaft 18 upon which the wheel 8 is mounted, being held in place by the removable key 19. 105 When the parts are in the position shown in Fig. 1 and the drum 6 is rotated, the machine will be fed laterally. The arm 9 is adjusted to secure the proper position of the rear end of the machine, and, by its 110

contact with the flexible power transmitting device 5, prevents the rear end of the machine from being fed forward too rapidly. The part 14 moves along the flexible power transmitting device 5 as the machine is fed laterally until the machine approaches the wall (see Figs. 3 and 4). When the part 14 reaches the wall, so that further movement of the machine is prevented, the arm 9 is 10 detached, and the part 14 and brace 17 are removed or moved to a position where they will be out of the way. The arm 9 is then brought into engagement with the wall 20, said arm being preferably provided with a 15 point for this purpose. The machine is then fed laterally again, the arm being gradually shortened as required by rotating the sleeve 11. When the arm 9 can no longer be shortened, it is then moved to 20 various angular positions, as shown in Fig. 4, and the front end of the machine then moves around as shown in Fig. 4. When the end of the cutter reaches the line of the wall 20 the entire machine is then moved 25 back so as to cut away the wedge-shaped portion 21.

I claim:—

1. A mining machine comprising a frame, a cutter projecting therefrom, a flexible power transmitting device adapted to be connected with a fixed part at a distance from the frame, a rotatable part on the frame, with which said flexible power transmitting device is connected, an arm connected with said frame, a brace connected with said frame and extending along said flexible power transmitting device, said arm and brace connected together at an angle to each other, means for movably contacting said arm and brace with said flexible power transmitting device, a direction changing device which engages said flexible power transmitting device, the portions of said flexible power transmitting device on opposite sides of said direction changing device forming two sides of a triangle, said arm forming the other side of said triangle.

2. A mining machine comprising a frame, a cutter projecting therefrom, a flexible power transmitting device for moving said frame and cutter laterally to feed the machine along the coal, a retarding device for retarding the movement of the rear end of the machine, comprising an arm connected with said machine, and a brace connected with said frame and arm and substantially parallel with a portion of said flexible power transmitting device, said brace and arm movably contacting with said flexible power

transmitting device, said arm being adjustable so that its length may be varied.

3. A mining machine comprising a frame, a cutter projecting therefrom, means for moving said machine laterally while in operation so as to feed the cutter toward the material to be acted upon, and an adjustable arm pivotally connected with the rear end of the machine, a resisting part, said adjustable arm interposed between said frame and said resisting part, whereby the adjustable arm holds said resisting part against movement by the power transmitting device, the end of said arm nearest said resisting part being removably connected in position and being provided with an engaging part adapted to be brought into engagement with the wall when the end of said arm is disconnected and the machine approaches the end of the cut.

4. A mining machine comprising a frame, a cutter projecting therefrom, a flexible power transmitting device adapted to be connected with a fixed part at a distance from the frame, a rotatable part on the frame, with which said flexible power transmitting device is connected, a brace connected with said frame, a contacting device on each end of said brace which engages said flexible power transmitting device, and an arm connected with said brace and pivotally connected with said frame, said arm removably connected with said brace at one end so that it can be removed therefrom and moved about its pivotal connection to be brought into engagement with a fixed part as the machine approaches the end of its cut.

5. A mining machine comprising a frame, a cutter projecting therefrom, a flexible power transmitting device connected with a rotating part on the frame and with a fixed part at a distance therefrom, said flexible power transmitting device forming two sides of a triangle, a contacting part adapted to contact with said power transmitting device, a removable brace connecting the contacting part and said frame, a longitudinally adjustable arm connected with the rear end of said frame and interposed between said contacting part and said frame so as to resist the movement of said engaging part, said longitudinally adjustable arm forming the third side of said triangle.

CHARLES A. PRATT.
